UNITED STATES PATENT OFFICE.

AARON MENDELSON AND SHEPARD J. GOLDBERG, OF NEW YORK, N. Y.

CIGARETTE-BOX.

1,101,311.

Specification of Letters Patent. Patented June 23, 1914.

Application filed October 4, 1913. Serial No. 793,414.

To all whom it may concern:

Be it known that we, AARON MENDELSON and SHEPARD J. GOLDBERG, citizens of the United States, and residents of the city of New York, borough of Brooklyn, in the county of Kings and State of New York, have invented a new and Improved Cigarette-Box, of which the following is a full, clear, and exact description.

10 This invention relates to cigarette boxes and more particularly to a box which may be constructed of pasteboard or metal, to form a neat and attractive article designed for permanent use so that cigarettes may be 15 removed from the ordinary boxes and placed within a series of clamps or holders supported in a novel manner in the body of the box, whereby a person or persons may readily remove a single cigarette.

20 A further object of the invention is to provide a supporting member which is hinged in the body of the box and designed to normally move to an upright position when the cover of the box is opened, the 25 said supporting member carrying holders or clamps designed to move into spaced relation automatically upon the opening of the box.

With the above and other objects in view, 30 the invention resides more particularly in the peculiar combination and arrangement of parts which will be illustrated as a preferred embodiment in the accompanying drawings and described in the specification.

35 Reference is to be had to the accompanying drawings forming a part of this specification, in which similar characters of reference indicate corresponding parts in all the views, and in which

40 Figure 1 is a perspective view of a cigarette box constructed in accordance with the invention, the same being shown in an open position with the supporting members for the cigarettes in an upright position where- 45 by the cigarettes may be removed; Fig. 2 is a longitudinal sectional view of the device in the position shown in Fig. 1; and Fig. 3 is a plan view of the box with the sup- porting member moved into the body, the 50 cover being broken away to show the ar- rangement of the parts when the box is closed.

55 As shown, the box comprises a body 5 preferably having flat front and rear edge portions 6 and 7 and convexed side edges 8 preferably formed by bending the bottom

of the body upwardly. Hinged to the rear edge portion 7, as shown at 9, is a cover 10 preferably having its marginal edges turned inwardly, as shown at 11, and having downwardly directed portions adapted to snap into the area of the body, while a suitable flap 12 at the free edge of the cover is designed to retain the cover in a closed position by engagement with the inturned edge 13 of the part 6.

A supporting member or plate 14 is pivotally mounted in the body near the back portion of the latter, and for this purpose the opposite sides of the body are provided with bearing portions or blocks 15 mounted in the concaves of the edge portions 8 and designed to receive the ends of the pivot 16. The supporting member or plate 14 is provided with spaced end ears 17 pivotally engaged with the pivot or pintle 16, such ears being formed by severing the plate at spaced points to provide an intermediate extension 18 which is directed downwardly and rearwardly in angular relation to the plate proper so as to form a limiting member preventing the plate or supporting member from moving beyond an upright position, as is clearly shown in Fig. 2 of the drawings. The plate is 85 normally sustained in this position by a pair of springs 19 around the pintle or pivot 16 beyond the ends of the supporting member or plate, and each spring is provided with a curved arm 20 bearing against 90 the bottom of the box body and with an angular arm 21 engaging the front face of the supporting member or plate, so that when the cover 10 is open said supporting member or plate will automatically move 95 to an upright position. The utility of this structure and function is apparent, by providing a plurality of clamps or holders upon the supporting member or plate designed to hold the cigarettes 22 at different elevations 100 or in spaced relation as shown. The holders or clamps, indicated by the numeral 23, in the present instance are alternately fixed to or pivoted with respect to the supporting member or plate 14 near the lower edge 105 of the latter, and each clamp or holder is made up of a single section or strip of metal having a back portion 24, a bottom portion 25 disposed at right angles thereto and a front portion 26 bent upwardly in spaced relation to the back portion. The front and back portions are disposed in such position

as to clamp a cigarette held therebetween, and in order to permit the cigarettes to readily enter the holders or clamps the upper edges of the front portions are bulged outwardly, as shown at 27, the edge portions being convexed as shown.

Certain of the holders are fixed to the supporting member or plate through the instrumentality of rivets or the like 28 preferably 10 engaged near the back portions of the holders, while the other holders or clamps are bent to form integral ears 29 engaged through transverse slots 30 in the supporting member or plate and retained in 15 position upon a pivot 31 so that while the first-mentioned holders are held in an upright position coinciding with that of the supporting member or plate, the pivoted holders or clamps will move into inclined 20 positions and thus dispose the cigarettes in spaced or staggered relation and at different elevations when the cover is open and the supporting member or plate is automatically moved by the springs to an upright position. 25 Thus the device possesses advantages both in structure and utility, since the cigarettes will not only be firmly held against accidental displacement but may be readily withdrawn independently and without fingering the 30 other cigarettes in the box.

Having thus described our invention, what we claim as new and desire to secure by Letters Patent is:—

1. In a cigarette box, the combination 35 with a box body and cover therefor; of a supporting plate pivoted in the box body, a plurality of cigarette holders carried by said plate, certain of said holders being rigid with the plate and others pivoted to swing in 40 spaced relation thereto when the box is open, and means to move the supporting plate to a vertical position.

2. The combination with a box comprising 45 a body portion and a cover therefor; of a plate pivoted to the opposed sides of the box body, spring means normally elevating the plate at right angles to said body, means to

limit the movement of the plate at the last-named position, and a plurality of clamps fixed to the plate near its bottom portion. 50

3. The combination with a box comprising a body portion and a cover therefor; of a plate pivoted to the opposed sides of the box body, said plate having an angular extension adapted to contact with the bottom of the 55 box body to limit the movement of the plate to an elevated position, spring means carried by the pivot of the plate and engaging the plate and body to hold said plate in an elevated position, and clamps carried by the 60 opposed sides of the plate in spaced relation.

4. The combination with a cigarette box, a supporting plate carried therein and means adapted to move said plate into an accessible position when the box is open; of a plurality of cigarette holders carried by the plate, said holders comprising single sections of material re-bent to provide spaced front and back portions and a bottom portion, the upper ends of the front portion being bulged 70 outwardly.

5. The combination with a cigarette box, a supporting plate carried therein and means to move the plate into accessible position when the box is open; of a plurality of cigarette holders carried by the plate, said holders comprising single sections of material re-bent to provide spaced front and back portions and a bottom portion, the upper ends of the front portion being bulged outwardly, 75 the holders in alternate relation being fixed to and pivotally carried by the plate whereby the cigarettes carried therein will be held adjacent to and in angular relation to the plate when the box is open and will move 80 into alignment when the box is closed.

In testimony whereof we have signed our names to this specification in the presence of two subscribing witnesses.

AARON MENDELSON.
SHEPARD J. GOLDBERG.
